UNITED STATES PATENT OFFICE.

LABAN TAYLOR FREEMAN, OF BROOKVILLE, MISSISSIPPI.

EDUCATIONAL APPLIANCE.

1,093,690.

Specification of Letters Patent. Patented Apr. 21, 1914.

Application filed August 24, 1912. Serial No. 716,857.

To all whom it may concern:

Be it known that I, LABAN T. FREEMAN, a citizen of the United States, residing at Brookville, in the county of Noxubee and State of Mississippi, have invented a new and useful Educational Appliance; and I do hereby declare the following to be a full, clear, and exact description of the invention, such as will enable others skilled in the art 10 to which it appertains to make and use the same.

This invention relates to the art of calculating devices, and particularly to a machine, whereby adding and subtracting may 15 be accomplished without difficulty.

As some of the features of the invention, it is the aim to provide a device having a series of stationary columns of numerals from 1 to 18 inclusive, and a series of belts, 20 each having a column of numerals from 1 to 150 inclusive, and arranged to move parallel with the stationary columns, the belts adapted to be manipulated in such manner, that problems in addition and subtraction 25 may be effected easily and with mechanical certainty.

The invention comprises further features and combinations of parts, as hereinafter set forth, shown in the drawings and claimed.

30 In the drawings:—Figure 1 is a perspective view of the calculating device constructed in accordance with the invention. Fig. 2 is an elevation showing the first step in a problem of addition. Fig. 3 is a fragmentary view in elevation showing the second step. Fig. 4 is a view similar to Fig. 3 showing the third step or the result of the addition. Fig. 5 is a sectional view on line 5—5 of Fig. 1. Fig. 6 is a detail view of one 40 of the belts. Fig. 7 is an enlarged detail sectional view on line 7—7 of Fig. 1.

Referring more especially to the drawings, 1 designates a box-like structure, which may be of any desired dimension, suitable 45 for the purpose intended. The front face of the box is divided into six spaces by the lines 2, the spaces being denoted by the numerals 3. Adjacent the lower portion of each line 2, a series of spaces 4 are provided, one above the other numbered from 1 to 18 inclusive, thereby constituting stationary columns of numerals. The lower portion of the front face of the box is provided with a series of slots alternating with 50 the columns of numerals 1 to 18, and through which slots the numbers (1 to 150

inclusive) upon the belts 7 are readable. These slots 6 merge into a transverse slot or opening 8 of the front of the box.

The boxlike structure 1 is provided with 60 openings 9 and 10, through which the belts 7 are visible, but are not a part of the invention claimed in this case.

Journalized in bearings of the box above and below are shafts 11, on which cog wheels 65 12 are rotatable. The belts 7 are provided with perforations 13 alternating with the numerals, 1 to 150 inclusive of said belts. These belts engage the cog wheels, the cogs passing through the perforations 13, thereby 70 preventing lateral movement of the belts relative to the wheels. Furthermore, these perforations serve to receive the point of a lead pencil, whereby the belts may be moved. Before accomplishing a problem, the belts 75 are disposed so that the numerals 1 of the belts appear opposite the numerals 1 of the stationary columns of numerals 1 to 18 inclusive.

If it is desired to add 222, 222 and 222, 80 the total of which is 666, the operator inserts a pencil point in the aperture just below the numeral 2 of the first belt, which numeral 2 is opposite the numeral 2 of the stationary column 1 to 18 next to the first 85 belt. The belt is moved until the pencil engages the lower edge of the slot 8, and the numeral 2 will appear through the slot 8. The operator then moves the second and third belt likewise. The operator then inserts 90 the pencil point in the aperture just below the numeral 4 of the first belt which also appears opposite the numeral 2 of the first stationary column of numerals 1 to 18, moving the first belt until the pencil contacts with the lower edge of the slot 8. The second and third belts are again likewise moved, thus it will be seen that 444 95 appears through the slot 8 as shown in Fig. 3. The operator then for the third and last 100 time inserts the pencil point in the aperture below the numeral (which is 6) of the first belt appearing opposite the numeral 2 of the first stationary column of the numerals 1 to 18 inclusive, moving the first belt as 105 before, until the pencil contacts with the lower edge of the slot 8. The second and third belts for the third and last time are likewise moved, in which case it will be seen that 666 appears through the slot 8 as shown 110 in Fig. 4, which is the sum total of 222, 222 and 222. If it is desired to add 256 and 124,

the operator inserts the pencil point in the aperture below the numeral (which is 6) appearing opposite the numeral 6 in the stationary column of numerals 1 to 18 moving 5 the first belt until the pencil contacts with the lower edge of the slot 8. The pencil is then inserted in the aperture of the second belt below the numeral (which is 5) opposite the numeral 5 of the second column of 10 stationary numerals 1 to 18 moving the second belt like the first. The pencil point is then inserted in the aperture of the third belt below the numeral (which is 2) opposite the numeral 2 of the third column of 15 stationary numerals 1 to 18. So far it will be seen that 256 may appear through the opening or slot 8. The pencil point is then inserted in the aperture of the first belt below the numeral (which is 4) opposite the 20 numeral 4 of the first stationary column of numerals, moving the first belt as before, then it will be seen that 10 of the first belt may appear through the slot 8. It will now be noted that it is necessary to carry the 25 number 1 of this 10, in adding the second column of 256 and 124. In accomplishing this the pencil point is placed in the aperture below the numeral (which is 6) appearing opposite the numeral 1 (which is 30 the numeral to be carried) of the second column of stationary numerals 1 to 18, moving the second belt as before until the pencil engages the lower edge of the slot 8. In this way the numeral 1 is carried. Now to 35 add the numeral 2 of 124, the pencil point is inserted in the aperture below the numeral (which is 8) opposite the numeral 2 of the stationary column of numerals 1 to 18, moving the second belt as before, in which 40 case number 8 will appear through the slot 8. The pencil point is then inserted in the aperture below the numeral (which is 3) of the third belt opposite the numeral 1 (which is the number of the third column of 124 to 45 be added) of the third column of numerals 1 to 18, moving the third belt until the pencil contacts with the lower edge of the slot 8. In this manner it will be seen that 380 appears through the slot 8, and which 50 is the sum total of 256 and 124. In reading this sum total, the numeral 10 of the first belt appearing through the slot 8 should only be read as a cipher disregarding the one, which was carried, in adding the second 55 column of 256 and 124.

If it is desired to subtract 43 from 125, the difference being 82, the pencil point is inserted in the aperture below the numeral (which is 3) opposite the numeral 3 of the 60 stationary column of numerals 1 to 18. Pull the first belt down until the pencil contacts with the lower edge of the slot, and if space upon the drawing would permit it, the numeral 5 (which is the number from which 65 3 is being subtracted) would appear oppo-

site the numeral 2 (which is the difference in subtracting 3 from 5) of the stationary column of numerals 1 to 18. Then by inserting the pencil in the aperture below the numeral (which is 4) of the second belt opposite 4 70 of the second column of stationary numerals 1 to 18, after which the second belt may be pulled down until the pencil contacts with the lower edge of the slot. If space would permit, it would be seen that the numeral 12 75 (which is the number from which 4 is being subtracted) would appear opposite the numeral 8 (which is the difference in subtracting 4 from 12) of the stationary column of numerals 1 to 18. In reading the difference in subtracting small numbers, the answer is read from the stationary columns of numerals, thus if space would permit it could be seen that 82 could be read from the 80 first and second columns of numerals 1 to 18, the 8 being opposite 12 of the second belt and 2 opposite the 5 of the first belt.

Upon the face of the box is provided a series of spring arms 14, the free ends of which have lugs 15, which enter apertures 16 90 of the face of the box. These lugs 15 have rounded ends, which extend into the perforations 13, in order to prevent slipping of the belts after being moved. However, owing to the rounded ends the belts will ride 95 past the lugs 15 when sufficient pressure is applied, the spring arms yielding sufficiently to permit the same. The belts will also slightly give in riding over said lugs 15.

The invention having been set forth, what 100 is claimed as new and useful is:—

In a calculating device, a box like structure, the front face of which is provided with vertical spaces, a column of spaces numbered 1 to 18 inclusive on the lower 105 right hand portion of each vertical space, the front face of the box like structure being provided with a plurality of vertical slots, one being located in the lower portion of each vertical space to the left of the column of spaces 1 to 18, the front face of the box having a transverse slot into which said vertical slots merge, shafts mounted in bearings in the upper and lower portions of the box and provided with a plurality of cog 110 wheels, endless belts having series of apertures or perforations throughout their length traveling about said wheels, the apertures or perforations receiving said cogs, each endless belt having a series of numerals 115 from 1 to 150 alternating with the apertures and adapted to coöperate with the numerals 1 to 18 of the numbered spaces above mentioned, whereby problems in addition may be performed, the sum total of a problem in 120 addition designed to appear in the lower ends of said vertical slots, when the belts are moved to effect a problem, said perforations or apertures constituting means to receive a pencil point to move the belts, 125 130

spring devices on the face of the box having means to penetrate the face of the box to enter the perforations of the belts, whereby the belts may be moved a numeral at a time, the 5 belts operating adjacent to and in the rear of said vertical slots.

In testimony whereof I have signed my

name to this specification in the presence of two subscribing witnesses.
